ADJUSTABLE HOLDER FOR LIPSTICKS
AND THE LIKE

Howard F. Reichenbach, Waterbury, Conn., assignor to Chase Brass & Copper Co. Incorporated, Waterbury, Conn., a corporation

Application June 9, 1941, Serial No. 397,159

2 Claims. (Cl. 206—56)

The present invention relates to improvements in adjustable holders and more particularly to adjustable holders for lipsticks and similar materials.

One of the objects of the present invention is to provide a superior holder of the character referred to which is convenient and reliable in operation and which may be produced at a low cost for manufacture.

Another object of the present invention is to provide an adjustable holder for lipsticks and the like having a carrier therein which is provided with a finger-piece of superior character.

With the above and other objects in view, as will appear to those skilled in the art from the present disclosure, this invention includes all features in the said disclosure which are novel over the prior art and which are not claimed in any separate application.

In the accompanying drawing, in which certain modes of carrying out the present invention are shown for illustrative purposes:

Fig. 1 is a view in side elevation of an adjustable lipstick-holder embodying the present invention;

Fig. 2 is a similar view of the adjustable lipstick-holder but viewing the same from a direction at a right angle to the showing of Fig. 1;

Fig. 3 is an elevational view corresponding to Fig. 1, save that the cap has been removed;

Fig. 4 is a view partly in side elevation and partly in central-longitudinal section taken on the line 4—4 of Fig. 1 but on a larger scale;

Fig. 5 is a transverse sectional view taken on the line 5—5 of Fig. 4;

Fig. 6 is a perspective view of the carrier or elevator detached; and

Fig. 7 is a plan view of a blank from which the carrier may be formed.

The particular adjustable lipstick-holder herein chosen for purposes of illustrating one embodiment of the present invention includes a cup-shaped body-member 10, an inverted cup-shaped cap 11 and a substantially-tubular carrier or elevator 12.

The cup-shaped body-member 10 comprises a cylindrically-contoured side-wall 13 and a substantially-flat bottom-wall 14. For purposes of strength and attractiveness, the lower portion of the side-wall 13 of the said body-member 10 is provided with three (more or less) annular beads 15. Intermediate its respective opposite ends the body-member 10 is formed with a longitudinally-extending clearance-slot 16 which is closed at its lower end but which communicates with the up-

per edge of the side-wall 13 of the body-member 10 by means of a narrow slot 17 serving to permit the upper portion of the said side-wall 13 to be expanded for assembly purposes.

5 Mounted within the cup-shaped body-member 10 with capacity for axial reciprocation therein is the carrier or elevator 12 before referred to. The said carrier or elevator 12 is provided with an integral finger-piece generally designated by the reference character 18, and including a head 19 and a shank 20 which extends outwardly through the longitudinal clearance-slot 16 in the cylindrically-contoured side-wall 13 of the body-member 10.

When the carrier or elevator 12 is depressed into its lowermost position, as shown particularly well in Fig. 4, and in which the lower edge of the shank 20 of its finger-piece 18 rests against the bottom-wall of the clearance-slot 16 in the body-member 10, the inverted cup-shaped cap 11 may be applied over the said body-member so that the lower edge of the said cap abuts against the upper edge of the uppermost one of the three annular beads 15 on the lower end of the said body-member. For the purpose of clearing the outwardly-extending shank 20 of the finger-piece 18, the cap 11 is formed in its lower edge with a downwardly-opening clearance-notch 21 which is substantially "covered," so to speak, when the said cap is in place, by the head 19 of the finger-piece 18.

20 The carrier or elevator 12 may be conveniently formed from a strip of sheet brass or other suitable material cut into a blank such as 22 shown in Fig. 7. The said blank includes a relatively-wide body-reach indicated at 23 in Fig. 7, and at its left side as viewed in the said figure, the blank is formed with a relatively narrow and short extension which for purposes of description 25 may be divided into two portions, namely, a shank-reach 24 and an interlocking-finger reach 25, indicated by broken lines. At its end opposite the reaches 24 and 25 the blank 22 is formed with an extension which is narrower than the width of the body-portion 23 thereof and which includes a shank-reach 26, a back-reach 27, a face-reach 28, and an interlocking-finger reach 29, the said reaches being shown as divided from each other by broken lines.

30 20 When the blank 22 by suitable forming operations is converted into the carrier or elevator 12 as particularly well shown in Fig. 6, the body-reach 23 becomes the body-portion 23a, the shank-reach 24 of the said blank becomes a radially-extending shank-portion 24a, while the in-

40 45 50 55

terlocking-finger reach 25 is bent outwardly in a generally tangential direction to form an interlocking-finger 25a. The shank-reach 26 of the blank 22 becomes a shank-portion 26a which extends in parallelism with and in substantial contact with the complementary shank-portion 24a before referred to. As thus formed into the completed carrier 12, the back-reach 27 of the said blank extends in a substantial circumferential direction from the outer end of the shank-portion 26a to form a back-portion 27a for the head 19 of the finger-piece 18. The face-reach 28 of the blank 22 is folded in a reverse direction from the back-portion 27a to form a circumferentially-curved face-portion 29a for the head 19 of the finger-piece 18. The interlocking-finger reach 29 of the blank 22 becomes in the finished carrier or elevator an interlocking-finger 29a reversely bent from the face-portion 28a to, in effect, clamp the interlocking-finger 25a against the rear face of the face-portion 28a.

It has heretofore been proposed to provide the carriers or elevators of lipstick-holders with integral finger-pieces, but all such prior structures have been open to numerous objections, among which may be mentioned weakness and ugly appearance. With the present construction, the finger-piece is not only a secure and rigid extension of the body-portion of the carrier itself with which it is integral, but the said finger-piece has both actual solidity and the attractive appearance of being substantial and solid.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. An adjustable holder for lipsticks and the like, comprising: a hollow body-member having a side-wall formed with a substantially-longitudinal slot; and a carrier formed of sheet material and axially movable in the said body-member, the said carrier including a body-portion bent into tubular form with juxtaposed edge-portions; a first shank-portion integral with and extending outwardly from one of the said juxtaposed edge-portions of the said body-portion through the slot in the said body-member, a second shank-portion integral with and extending outwardly from the opposite contiguous edge-

portion of the said body-portion and through the slot in the said body-member, a first interlocking-finger integral with and bent from the outer end of the said first shank-portion in a direction away from the said second shank-portion; a back-portion integral with and bent from the outer end of the said second shank-portion in a direction away from the said first shank-portion, a face-portion integral with and bent from the outer end of the said back-portion and extending over the front face of both the said back-portion and the said first interlocking-finger of the said first shank-portion, and an interlocking-finger integral with and reversely bent from the outer end of the said face-portion into substantial engagement with the back face of the said first interlocking-finger of the said first shank-portion.

2. An adjustable holder for lipsticks and the like, comprising: a hollow body-member having a cylindrically-contoured side-wall formed with a substantially-longitudinal slot; and a cylindrically-contoured carrier formed of sheet material and axially movable in the said body-member, the said carrier including a cylindrically-contoured body-portion bent into tubular form with juxtaposed edge-portions; a first shank-portion integral with and extending substantially radially outwardly from one of the said juxtaposed edge-portions of the said body-member and through the slot in the said body-member, a second shank-portion integral with and extending substantially radially outwardly from the opposite contiguous edge-portion of the said body-portion through the slot in the said body-member, a first interlocking-finger integral with and bent in a substantially-circumferential direction from the outer end of the said first shank-portion and in a direction away from the said second shank-portion; a back-portion integral with and bent in a substantially-circumferential direction from the outer end of the said second shank-portion and in a direction away from the said first shank-portion, and a concavo-convex face-portion integral with and bent from the outer end of the said back-portion and extending over the front face of both the said back-portion and the said first interlocking-finger of the said first shank-portion, and an interlocking-finger integral with and bent from the outer end of the said concavo-convex face-portion in a reverse direction with respect thereto into substantial engagement with the back face of the said first interlocking-finger of the said first shank-portion.

HOWARD F. REICHENBACH.
